MULTILEGGED CRUTCH

Stanley E. Du Bois, Piqua, Ohio

Application May 11, 1948, Serial No. 26,302

9 Claims. (Cl. 155—22)

1

This invention relates to crutches, and more particularly to a self-supporting multi-legged crutch adapted to be held by both hands of the user.

One of the principal objects of the invention is to provide such a crutch device which is of simple and light-weight construction for easy use, which possesses adequate strength for relatively severe treatment, and wherein all the component parts are secured together for ready collapsing movement when the device is not in use without requiring detachmeint of any parts and thus minimizing the possibility of loss or misplacement of the parts.

Another object is to provide a readily collapsible, multi-legged crutch which has a single handle portion to which the legs are attached and at least four foot portions for contact with the floor or ground at relatively widely spaced points when the device is set up for use to give firm support for the user with minimum danger of upsetting.

It is also an object of the invention to provide a multi-legged crutch having a single handle to which the legs are secured for relative movement between the collapsed and erected positions and having also a brace member movably connected with the legs in such manner as to move readily between a collapsed position in substantially the same plane as the legs and an operative position for rigidly bracing the legs when the device is set up.

Other objects and advantages will be apparent from the following description, the accompanying drawing and the appended claims.

In the drawing

Fig. 1 is a perspective view of a multi-legged crutch in accordance with the invention showing the device set up for use;

Figs. 2 and 3 are views in top plan and side elevation, respectively, showing the crutch set up;

Fig. 4 is a view in side elevation showing the crutch in an intermediate position between its collapsed and erected positions;

Fig. 5 is a similar view showing the crutch completely collapsed;

Fig. 6 is an enlarged detail sectional view through the handle of the crutch as indicated by the line 6—6 of Fig. 5; and

Figs. 7 and 8 are enlarged detail views on the lines 7—7 and 8—8, respectively, of Fig. 3.

In accordance with the present invention there is provided a multi-legged crutch which is especially well suited for use by individuals lacking the strength or muscular coordination to use con-

2

ventional single legged crutches, for example, victims of spastic paralysis, paraplegics or persons too old or otherwise infirm to possess adequate sense of balance to use conventional crutches, such as persons regaining the use of their legs following recovery from serious illness or injury. The invention provides a multi-legged crutch which is light in weight and thus easily manipulated by such individuals and includes at least four feet so spaced with relation to the handle as to give a wide supporting base minimizing the danger of tipping over even if the user is relatively off balance. The crutch includes a brace effective to secure the legs in rigid relation when the device is set up, but this brace is readily releasable for collapsing movement with the legs to a substantially flat position for ready storage. Furthermore, the releasing and collapsing or setting up movement of the crutch does not require the attaching or detaching of any of the parts but merely the releasing or tightening of a simple sliding clamp member, thus not only guarding against loss or misplacement of any of the parts but also greatly facilitating setting up or collapsing of the device by individuals lacking normal powers of coordination.

Referring to the drawings, which illustrate a preferred embodiment of the invention, the crutch includes a handle portion 10 in the form of a bar of wood or other suitable material shaped at each end for ready gripping by the hands of the user. Two rear legs 11 are secured to handle 10 in axially spaced relation and extend downwardly therefrom in diverging relation, the legs 11 and handle 10 being arranged to define a common plane as shown in Figs. 3 to 5. In assembling these parts, satisfactory results have been obtained by threading the upper ends of legs 11 into the handle and reinforcing this joint by glue to provide a rigid permanent connection.

A third or front leg 12 is connected to the handle 10 between the rear legs 11 for swinging movement with respect to the rear legs. The upper end of front leg 12 is secured to a cylindrical sleeve 13 rotatably mounted on the handle between the upper ends of the rear legs, means such as screws 14 (Fig. 6) being set in the handle at either end of sleeve 13 to keep the sleeve in axially fixed relation on the handle. Satisfactory results have been obtained by forming both leg 12 and sleeve 13 of metal tubing and welding them together. The front leg 12 is shorter than rear legs 11, and a yoke 15 of metal tubing or other suitable material is welded or otherwise secured to the lower end of leg 12 to provide a pair

of feet 16 spaced laterally of the device, each of these feet and the lower ends of rear legs 11 being shown as provided with rubber foot members 17 to minimize slipping of the device in use.

A brace is provided for bracing legs 11 and 12 in rigid relation when the device is set up for use, the brace being movably connected with the legs for collapsing movement with front leg 12 into substantially the same plane as the rear legs. The brace member 20 is formed of hollow tubing in generally Y-shape, and it includes two arm portions 22 pivotally connected to the rear legs 11. As shown in Fig. 7, the rearward end of each arm 22 is flattened at 23 to receive a rivet 24 forming a pivotal connection to a bracket 25 bolted or otherwise secured to one of legs 11 as indicated at 26. The flattened portion 23 of each arm 22 is also bent at an angle to the length of the arm and positioned inwardly of its associated rear leg 11 to provide for swinging movement of brace 20 into substantially the same plane as the rear legs. The arms 22 are further braced with relation to each other by a cross rod 27 welded or otherwise secured thereto.

The tail portion 28 of brace 20 is formed by flattening and welding together the front ends of arms 22 as shown in Fig. 8, and this end of the brace is pivotally and slidably connected to the front leg 12. A releasable clamp member 30 is slidably mounted on leg 12, and its two end portions overlap the part 28 of the brace. A bolt 32 traverses the ends of clamp 30 and the part 28 to form a pivotal connection therebetween, and this bolt is provided with a wing nut 33 to facilitate tightening and loosening of the clamp. The proportions of this clamp are such that when the wing nut is tight on bolt 32, clamp 30 is clamped against sliding movement on leg 12; but when nut 33 is loosened the clamp can readily slide on leg 12.

Figs. 1 to 3 show the device set up and ready for use. The user stands in the space outlined by the handle 10 and rear legs 11 as viewed in Fig. 2 and grips the two ends of the handle. To walk, he moves the device forward and then follows with his body, supporting himself on the device with his hands during each step. The device provides firm and steady support for such use, the spaced feet of the front legs 12 cooperating with the rear legs 11 to give a wide base capable of withstanding substantial angular thrust on the handle in any direction without danger of tipping or upsetting.

This construction also facilitates quick and easy collapsing of the device when it is not in use as well as ready setting up for use, and it will be noted that such collapsing operation does not require disconnection of any parts and thus minimizes the possibility of loss of a part. To collapse the device from the position shown in Figs. 1 to 3, it is necessary only to loosen the wing nut 33 and then to slide the clamp 30 up along front leg 12 while swinging the latter towards rear legs 11, thus causing the brace arms 22 to pivot upwardly on rivets 24 while the tail part 28 of the brace simultaneously pivots on bolt 32, this operation being illustrated in Fig. 4. When the device is fully collapsed, it is substantially flat as shown in Fig. 5, the legs 11 and 12 and the brace 20 all occupying substantially the same plane with handle 10. The nut 33 may then be tightened to hold the parts in collapsed relation, and the device can be readily stored in a minimum of space, for example by hanging in a closet.

or the like. To set up the device, the reverse sequence is followed, and when clamp 30 has moved all the way down leg 12 until it reaches the upper part of yoke 15, nut 33 is again tightened to secure all the parts in rigid relation for use.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A crutch device of the character described comprising a handle portion, a pair of rear legs secured to said handle and extending downwardly therefrom in rigid relation, said legs and said handle lying in substantially the same plane, a front leg connected with said handle between said rear legs for swinging movement relative to said rear legs about the axis of said handle substantially into and out of said plane, brace means effective to hold said legs in rigid relation when said front leg is swung out of said plane to set up said device, and means movably connecting said brace means with each of said legs to provide for collapsing movement of said brace means with said front leg substantially into said plane without relative detachment of any of said parts.
2. A crutch device of the character described comprising a handle portion, a pair of rear legs secured to said handle and extending downwardly therefrom in rigid relation, said legs and said handle lying in substantially the same plane, a front leg connected with said handle between said rear legs for swinging movement relative to said rear legs about the axis of said handle substantially into and out of said plane, said front leg being bifurcated at the lower end thereof to form a pair of laterally spaced feet, brace means effective to hold said legs in rigid relation when said front leg is swung out of said plane to set up said device, and means movably connecting said brace means with each of said legs to provide for collapsing movement of said brace means with said front leg substantially into said plane without relative detachment of any of said parts.
3. A crutch device of the character described comprising a handle portion, a pair of rear legs secured to said handle and extending downwardly therefrom in rigid relation, said legs and said handle lying in substantially the same plane, a front leg connected with said handle between said rear legs for swinging movement relative to said rear legs about the axis of said handle substantially into and out of said plane, means forming laterally spaced feet secured to the lower end of said front leg, brace means pivotally connected to each of said rear legs, and means for securing said brace means to said front leg to hold said legs in rigid relation when said device is set up, said securing means being releasable to provide for collapsing movement of said brace means substantially into said plane.
4. A crutch device of the character described comprising a handle portion, a pair of rear legs secured to said handle and extending downwardly therefrom in rigid relation, said legs and said handle lying in substantially the same plane, a front leg connected with said handle between said rear legs for swinging movement relative to said rear legs about the axis of said handle substantially into and out of said plane, brace means pivotally connected to each of said rear legs, means forming a slidably connection between said

brace means and said front leg to provide for collapsing movement of said brace means with said front leg substantially into said plane without relative detachment of said brace means and any of said legs, and means for releasably securing said slidably connection to said front leg to hold said brace means and said legs in rigid relation.

5. A crutch device of the character described comprising a handle portion, three legs, means connecting said legs with said handle in axially spaced relation and constructed to provide for swinging movement of the middle one of said legs with respect to the others of said legs into and out of a common plane containing said handle, means for bracing said legs in rigid relation when said middle leg is swung out of said plane to set up said device, and means pivotally and slidably connecting said bracing means with said legs to provide for relative collapsing movement of said bracing means with said legs without detachment therefrom.

6. A crutch device of the character described comprising a handle portion, a pair of legs rigidly secured to said handle in axially spaced relation and extending downwardly from said handle in diverging relation, said legs and said handle lying in substantially the same plane, a sleeve rotatably mounted on said handle between said legs, a third leg secured to said sleeve and swingable therewith about the axis of said handle, a yoke secured to the lower end of said third leg to form laterally spaced feet for said third leg, brace means effective to hold said legs in rigid relation when said front leg is swung out of said plane to set up said device, and means movably connecting said brace means with said legs to provide for collapsing movement of said brace means with said front leg substantially into said plane without detachment of said brace means from any of said legs.

7. A crutch device of the character described comprising a handle portion, a pair of legs rigidly secured to said handle in axially spaced relation and extending downwardly from said handle in diverging relation, said legs and said handle lying in substantially the same plane, a sleeve rotatably mounted on said handle between said legs, a third leg secured to said sleeve and swingable therewith about the axis of said handle, a yoke secured to the lower end of said third leg to form laterally spaced feet for said third leg,

a Y-shaped brace member pivotally connected to each of said pair of legs, and means for securing said brace member to said third leg to hold said legs in rigid relation when said device is set up, said securing means being releasable to provide for collapsing movement of said brace member substantially into said plane.

8. A crutch device of the character described comprising a handle portion, a pair of legs rigidly secured to said handle in axially spaced relation and extending downwardly from said handle in diverging relation, said legs and said handle lying in substantially the same plane, a sleeve rotatably mounted on said handle between said legs, a third leg secured to said sleeve and swingable therewith about the axis of said handle, brace means pivotally connected to each of said pair of legs, a releasable clamp slidably mounted on said third leg, and means pivotally connecting said brace means and said clamp to provide for collapsing movement of said brace means with said third leg substantially into said plane and for releasably securing said brace means and legs in rigid relation.

25 9. A crutch device of the character described comprising a handle portion, a pair of legs rigidly secured to said handle in axially spaced relation and extending downwardly from said handle in diverging relation, said legs and said handle lying in substantially the same plane, a sleeve rotatably mounted on said handle between said legs, a third leg secured to said sleeve and swingable therewith about the axis of said handle, a yoke secured to the lower end of said third leg to form laterally spaced feet therefor, a Y-shaped brace member

30 pivotally connected to each of said pair of legs, and releasable clamp means forming a sliding connection between said brace member and said third leg to provide for collapsing movement of said brace member with said third leg substantially into said plane and for releasably securing said brace member and legs in rigid relation.
